Application April 23, 1956, Serial No. 580,033

8 Claims. (Cl. 155—113)

This invention has to do with an article of furniture and is more particularly concerned with a convertible chair and couch.

The principle object of my invention is to provide an article of furniture adapted to be normally used as a chair, but which may be readily converted into a couch when desired.

It is an object of this invention to provide a chair-like structure having a seat, a back rest, and a pair of arm rests related to the seat and back rest, and adapted to pivot relative thereto to establish a couch, the said arm rests establishing the foot and head portions of the couch.

Another object of my invention is to provide an article of furniture of the character referred to having a mechanical actuating means for shifting the arm rests relative to the seat, and the back rest.

A further object of the present invention is to provide an article of furniture of the general character referred to which is simple in construction, durable and dependable in operation, and which is both neat and attractive in appearance.

The various objects and features of my invention will be more fully understood from the following detailed description of a typical preferred form and application of my invention, throughout which description reference is made to the accompanying drawings, in which:

Fig. 1 is a perspective view of the article of furniture that I provide and showing it in an unactuated or chair position. Fig. 2 is a perspective view of the article of furniture provided by the present invention and showing it in an actuated or couch position. Fig. 3 is a sectional view of the structure of the present invention, it being a view taken substantially as indicated by line 3—3 on Fig. 1. Fig. 4 is a back view of the construction provided by the present invention, taken substantially as indicated by line 4—4 on Fig. 3 and showing one arm rest in section. Fig. 5 is a back view, similar to Fig. 4 and showing the construction in an actuated or couch position.

The convertible chair and couch construction provided by the present invention and illustrated throughout the drawings, includes generally, a frame A having a flat, horizontally disposed base B, vertically disposed arm rest supports C and D at the ends of the base, a central seat portion E spaced between the arm rest supports and projecting upwardly from the base, and a back rest F projecting upwardly from the seat portion E. The structure further includes normally vertically disposed arm rests G and H pivotally carried by the arm rest supports to occur adjacent the seat portion E and back rest F and adapted to be pivoted relative thereto to establish a couch, and actuating means I carried by the frame A and adapted to shift or pivot the arm rest from one position to the other.

The base B of the frame A is an elongate flat member or structure having straight parallel front and rear sides 10 and 11 and straight parallel ends 12 and 13.

The arm rest supports C and D are flat, vertically dis-

posed rectangular members or structures, having straight horizontally disposed top edges 14 and 15, respectively. The arm rest supports C and D are fixed to the ends of the base B to project upwardly therefrom, with the top edges 14 and 15 thereof spaced above and extending transverse of the base.

The central seat portion E of the frame A is a box-like structure fixed to and projecting upwardly from the base B at a point intermediate the ends thereof and spaced from the supports C and D. The seat portion E is established by a pair of vertically disposed side walls 16 spaced longitudinally along the base and extending transverse of the base, and a flat horizontally disposed rectangular cover 17 fixed to and extending between the upper edges of the walls 16. The cover 17 has end portions 18 that overhang or project beyond the side walls 16 to establish downwardly facing stops 19 extending transverse of the frame and adapted to be engaged by portions of the arm rests G and H, in a manner that will be hereinafter described.

The back rest F of the frame H is a substantially flat vertically disposed structure and projects upwardly from the back side of the central seat portion E. In the form of the invention illustrated the back rest F is shown as including posts 20 secured to the base B and the side walls 16 of the seat portion E, and a flat rectangular, vertically disposed panel 21 fixed to the front sides of the posts to project upwardly from the cover 17 of the seat portion to the tops of the posts.

30 In the case illustrated the vertical end portions of the panel 21 project beyond the end portions 18 of the cover 17 of the central seat portion E.

In carrying out the present invention, the frame construction A thus far described can be fabricated of wood, metal or a combination of wood and metal, as desired and as circumstances require.

In the form of the invention illustrated the back rest F is suitably upholstered by a thick pad 22 of foam rubber, or the like, secured to the front surface 23 of the panel 21. The pad 22 extends from one end of the panel to the other and from the cover 17 of the seat portion E upwardly to the top of the panel. A suitable fabric or plastic covering 24 is provided to cover the front, top and ends of the pad.

45 The cover 17 of the seat portion E of the frame A can be upholstered in the same manner as the back rest F, or, as in the particular case illustrated, can support and be covered by a suitable cushion 25.

It is to be understood that the above manner of covering or upholstering the seat cover 17 and the back rest F of the frame A is only one possible manner in which each of said portions can be upholstered and that in practice any other suitable form of upholstery can be employed.

55 The arm rests G and H of the convertible chair and couch construction provided by the present invention and pivotally carried by the frame A, are substantially alike, and each includes, a frame-like body 30 and suitable upholstery 31.

60 The frame-like bodies 30 of the arm rests G and H are substantially flat vertically disposed rectangular structures having upper portions 32 projecting upwardly from the top edges 14 and 15 of the arm rest supports C and D, and lower portions 33 depending from the top portions to normally occur adjacent the inner sides of the arm rest supports and within the spaces defined by the supports C and D and the central seat portion E of the frame A.

70 In the form of the invention illustrated, the lower portions 33 of the arm rest bodies 30 are relieved or made narrower than the upper portions 32 so that downwardly facing shoulders 34 are established along the lower edges

of the upper portions 32, which shoulders oppose the top edges 14 and 15 of the arm rest supports C and D.

It will be further apparent that with the construction and relationship of parts set forth above, the outer end surfaces of the upper portions 30 of the arm rest bodies are flush with the outer end surfaces of the arm rest supports C and D, with the result that a neat and attractive point of joiner is established where the upper portions of the arm rest bodies join the arm rest supports.

The upholstery 31 on the arm rests G and H is shown as including pads 35 of foam rubber, or the like, and a suitable fabric or plastic covering 36. The pads 35 extend across the tops of the bodies 30 and continue down the inner surfaces of the bodies to terminate short of the lower edge portions 37 of the lower portions 33 of the bodies.

The upholstery 31 on the arm rests G and H is of substantial thickness and projects inwardly from the bodies 30 to occur adjacent the vertical ends of the back rest F and the ends of cushions 25 on the cover 17 of the seat portion E.

Suitable hinge means are provided at the top edges of the arm rest supports G and D to pivotally connect the arm rests G and H thereto. The hinge means is shown as including a simple elongate piano type hinge 37 at each end of the construction, having one flange fixed to and extending along the top edge of the arm rest support to which it is related, and having the other flange fixed to and extending along the downwardly facing shoulder 34 on the upper portion 32 of the arm rest body to which it is related, as clearly illustrated in Figs. 4 and 5 of the drawings.

With the relationship of parts set forth above, it will be apparent that the arm rests H and G can be pivoted relative to the arm rest supports C and D so that their upper portions project longitudinally from the ends of the frame A, the inner portions bridge the spaces between the supports C and D and the central seat portions E, and so that the inner surfaces of the upholstery 31 thereon are flush with, or suitably far into, or join with the top surface of the cushion 25 on the seat portion E, to establish a couch upon which a person can recline, or lie upon.

In the case illustrated, the arm rest G pivots outwardly from the support C to a horizontal position and forms a foot portion for the couch, while the arm rest H pivots outwardly from the support D and stops in an upwardly inclined position to establish a head portion for the couch, as clearly illustrated in Figs. 2 and 5 of the drawings.

When the arm rests G and H are actuated or pivoted outwardly relative to the supports C and D in the manner set forth above, the lower edge portions 37 of the arm rest bodies engage and stop against the downwardly facing stops 19 established by the overhanging end portions 18 of the cover 17, of the central seat portion E.

In the form of the invention under consideration, the ends 40 of the cushion 25 are inclined downwardly and inwardly, and the lower edges 41 of the upholstery 31 on the arm rests G and H are curved and/or inclined relative to the vertical inner surface thereof, so that when the arm rests are actuated or pivoted outwardly, the inner surfaces of the upholstery on the arm rests clear the ends 40 of the cushion 25 and the lower edges 41 of the arm rest upholstery cooperate with the ends 40 of the cushion 25, when the construction is fully actuated, to substantially close the space therebetween and establish a neat and attractive lapped relationship with each other, as clearly illustrated in the drawings.

In the form of the invention illustrated, the arm rest support D is slightly higher than the arm rest support C. With the above relationship of parts, it will be apparent that the arm rest G is permitted to pivot a full 90° to a horizontal position, while the pivotal movement of the arm rest H is limited, or restricted, and is stopped in an

inclined position, as clearly illustrated in Fig. 5 of the drawings.

It will be further apparent that by varying the vertical extent or height of the arm rest supports C and D, the angle of the arm rests G and H, when in the actuated position, can be varied, as circumstances require. It is to be understood however that the vertical extent of the upper portions 32 of the arm rest bodies must be varied to compensate for variations of the vertical extent of the arm rest supports, so that the arm rests are of equal height when in the vertical unactuated position.

With the structure thus far described, it will be apparent that the arm rests G and H are of substantial vertical extent and that when the construction is in an unactuated or chair position the lower portions of the arm rests occur below the top of the cushion 25 and are housed in the space between the arm rest supports and the central seat portion of the frame A. It will be further apparent that when the construction is actuated and in a couch position, the lower portions of the arm rests are brought into cooperative relationship with the cushion 25 so that a couch of suitable longitudinal extent is established.

The actuating means I adapted to shift or pivot the arm rests G and H relative to the arm rest supports C and D, the central seat portion E and the back rest F is shown as including, a reversible electric motor M carried by the base B, below the cover 17 of the central seat portion E, a reduction gear 50 on the base B and connected with the motor M, a drive pulley wheel 51 driven by the reduction gear, a driver pulley wheel 52 rotatably carried by the panel 21 of the back rest F, a pulley belt 53 between the drive and the driven pulleys, an elongate link 54 pivotally connected to and extending between the lower end of the arm rest C and the driven pulley wheel 52, and an elongate link 55 pivotally connected to and extending between the lower end of the arm rest H and the driven pulley wheel 52.

The links 54 and 55 of the means I are pivotally connected with and extend between the back side of the driven pulley wheel 52 and the back side of the lower end portions 37 of their related arm rests. The links 54 and 55 are of such longitudinal extent and are pivotally connected to the driven pulley wheel 52, at points, so that the arm rests G and H are moved from a fully unactuated position to a fully actuated position, upon rotating the pulley wheel 52 through 180° in the direction indicated by the arrow X in Fig. 4 of the drawings. It will be apparent that when the construction is in an actuated position, it can be returned to an unactuated position by rotating the pulley wheel 52 in the direction indicated by the arrow Y in Fig. 5 of the drawings.

In practice, it is preferred that the driver pulley wheel 52 be rotated slightly more than 180°, say for example, 185°, to shift the arm rests G and H from one position to the other, and that the links 54 and 55 be connected to the driven pulley wheel at positions or points spaced radially and circumferentially thereof so that they cross or go over the central axis of the pulley wheel as they reach their fully actuated or unactuated position.

It is also preferred that a suitable stop means 60 be provided for the driven pulley 52 so that when the wheel is rotated the desired amount, it is positively stopped and cannot rotate further in a manner to cause the arm rests to again pivot or shift.

In the case illustrated, the stop means 60 includes a suitable stop member 61 fixed to and projecting radially from the pulley wheel 52, and a stop block 62 fixed to each of the posts 20 of the back rest F, between which the pulley wheel is located, and adapted to be engaged by and to stop the member 61 and the pulley wheel 52.

With the above relationship of parts, it will be apparent that the actuating means I serves to lock the arm rests G and H in their fully actuated or unactuated positions.

When the actuating means I is operated to the fully actuated position, the links 54 and 55 must cross each other, in the manner illustrated in Fig. 5 of the drawings. In order to permit the links 54 and 55 to cross in the manner set forth above, the end of the link 55 connected to the pulley wheel 52 is held in spaced relationship from the back side of the pulley wheel and from the link 54 by the pivot means connecting the link 55 to the pulley wheel.

Since the pivot means connecting the pulley wheel 52 to the panel 21 of the back rest F and the pivot means connecting the ends of the links 54 and 55 to the pulley wheel 52 and the arm rests D and H, do not materially effect the novelty of the present invention, detailed illustration and description thereof will be dispensed with, it being understood that any suitable pivotal connecting means can, in practice, be employed.

In the form of the invention illustrated, the posts 20 of the back rest F project a substantial distance rearward of the panel 21 and the means I, and are provided with suitable notches 70 to freely pass the links 54 and 55 as they project from the pulley wheel 52 to the arm rests G and H.

In order to provide a neat, attractive construction, and to hide or shield the posts 20 of the back rest F and the actuating means I, a suitable horizontally disposed top board 80 and suitable vertically disposed end boards 81 are secured to the top and end edges of the panel 21 of the back rest, to project rearwardly therefrom. In practice, the upholstery covering 24 on the back rest F continues rearwardly from the top and ends of the pad and covers the boards 80 and 81.

To further enhance the appearance of my furniture construction, a suitable facing board 82 is secured to the front of the frame A to extend from one end thereof to the other and is adapted to close the front of the central seat portion E and the spaces occurring between the seat portion E and the arm rest supports C and D, so that no unsightly openings, spaces or gaps can be viewed at the front of the construction.

In the form of the invention illustrated, and to further enhance the appearance of the furniture construction that I provide, the covering 36 on the arm rests G and H, continues from the tops of the pads 35, downwardly over the outer or end surfaces of the arm rests and the arm rest supports C and D, and suitable covers and hide the hinges 37 that pivotally connect the arm rests and their related supports together.

The reversible motor M of the actuating means F is controlled by a suitable switch panel (not shown), which panel can be located at a station remote from the piece of furniture, and connected thereto by a suitable electrical cable.

It will be apparent from the foregoing, that the present invention provides a neat and attractive upholstered chair, which when desired, can be easily and quickly converted into an equally neat and attractive couch.

It will be further apparent that the article of furniture of the present invention is both easy and economical of manufacture, is strong and durable in construction and is dependable in operation.

Having described only a typical preferred form and application of my invention, I do not wish to be limited or restricted to the specific details herein set forth, but wish to reserve to myself any variations or modifications that may appear to those skilled in the art and fall within the scope of the following claims:

Having described my invention, I claim:

1. A convertible chair and couch of the character referred to including, an elongate frame having a flat base, arm rest supports projecting up from the ends of the base, a central seat portion projecting up from the base and spaced from the supports, and a back rest projecting upwardly from the central seat portion, arm rests having upper and lower portions, pivot means securing the arm

rest to the arm rest supports with the upper portions thereof projecting upwardly from the supports and the lower portions thereof depending between the supports and the central seat portion, and actuating means carried by the frame and connected with the arm rests and operable to pivot the arm rests from a position where their upper portions project upwardly from the supports to a position where their upper portions project longitudinally outward from the supports and where the lower portions of the arm rest are brought into cooperative engagement with the central seat portion.

2. A convertible chair and couch of the character referred to including, an elongate frame having a flat base, arm rest supports projecting up from the ends of the base, a central seat portion projecting up from the base and spaced from the supports, and a back rest projecting upwardly from the central seat portion, arm rests having upper and lower portions, pivot means securing the arm rest to the arm rest supports with the upper portions thereof projecting upwardly from the supports and the lower portions thereof depending between the supports and the central seat portion, and actuating means carried by the frame and connected with the arm rests and operable to pivot the arm rests from a position where their upper portions project upwardly from the supports to a position where their upper portions project longitudinally outward from the supports and where the lower portions of the arm rest are brought into cooperative engagement with the central seat portions, the central seat portion of the frame having downwardly facing stops at each end thereof to extend transversely of the frame and spaced above the base and adapted to be engaged by the lower portions of the arm rests when the arm rests are actuated.

3. A convertible chair and couch of the character referred to including, an elongate frame having a flat base, arm rest supports projecting up from the ends of the base, a central seat portion projecting up from the base and spaced from the supports, and a back rest projecting upwardly from the central seat portion, arm rests having upper and lower portions, pivot means securing the arm rest to the arm rest supports with the upper portions thereof projecting upwardly from the supports and the lower portions thereof depending between the supports and the central seat portion, and actuating means carried by the frame and connected with the arm rests and operable to pivot the arm rests from a position where their upper portions project upwardly from the supports to a position where their upper portions project longitudinally outward from the supports and where the lower portions of the arm rest are brought into cooperative engagement with the central seat portions, the central seat portion of the frame having downwardly facing stops at each end thereof to extend transversely of the frame and spaced above the base and adapted to be engaged by the lower portions of the arm rests when the arm rests are actuated, one support being of sufficient vertical extent so that the arm rest pivoted thereto is in a horizontal plane when fully actuated and stopped, the other support being of greater vertical extent so that the arm rest pivoted thereto is in an inclined position when fully actuated and stopped.

4. A convertible chair and couch of the character referred to including, an elongate frame having a flat horizontally disposed base with parallel front and rear sides and parallel ends, flat vertically disposed rectangular arm rest supports projecting upwardly from the ends of the base, a box-like central seat portion projecting up from the base and spaced from the arm rest supports, and a flat substantially vertically disposed back rest projecting upwardly from the back side of the central seat portion, a substantially flat, rectangular arm rest related to each arm rest support to extend transverse of the frame, each arm rest having a normally upwardly projecting upper portion projecting upwardly from the arm support to occur adjacent the central seat portion and the back rest, and a lower portion depending between the arm rest sup-

port and the central seat portion, hinge means securing the upper portions of the arm rests to the tops of the arm rest supports, and actuating means carried by the frame and connected with the arm rests and operable to pivot the arm rests to a position where their upper portions project longitudinally outward from the tops of the supports and their lower portions are brought into cooperative engagement with the central seat portion of the frame to establish a couch, the actuating means including, a reversible prime mover carried by the frame, a pulley wheel carried by the frame and driven by the prime mover, and a link extending between and pivotally connected with the lower end portion of each arm rest and the pulley wheel.

5. A convertible chair and couch of the character referred to including, an elongate frame having a flat horizontally disposed base with parallel front and rear sides and parallel ends, flat vertically disposed rectangular arm rest supports projecting upwardly from the ends of the base, a box-like central seat portion projecting up from the base and spaced from the arm rest supports, and a flat substantially vertically disposed back rest projecting upwardly from the back side of the central seat portion, a substantially flat, rectangular arm rest related to each arm support to extend transverse of the frame, each arm rest having a normally upwardly projecting upper portion projecting upwardly from the arm support to occur adjacent the central seat portion and the back rest, and a lower portion depending between the arm rest support and the central seat portion, hinge means securing the upper portions of the arm rests to the tops of the arm rest supports, and actuating means carried by the frame and connected with the arm rests and operable to pivot the arm rests to a position where their upper portions project longitudinally outward from the tops of the supports and their lower portions are brought into cooperative engagement with the central seat portion of the frame to establish a couch, the actuating means including, a reversible prime mover carried by the frame, a pulley wheel carried by the frame and driven by the prime mover, and a link extending between and pivotally connected with the lower end portion of each arm rest and the pulley wheel, and suitable upholstery on the central seat portion, on the back rest of the frame and on the arm rests.

6. A convertible chair and couch of the character referred to including, an elongate frame having a flat horizontally disposed base with parallel front and rear sides and parallel ends, flat vertically disposed rectangular arm rest supports projecting upwardly from the ends of the base and extending transverse the base, a box-like central seat portion projecting up from the center of the base and extending transverse the base, and a flat substantially vertically disposed back rest projecting upwardly from the back side of the central seat portion, the central seat portion having longitudinally spaced vertical side walls projecting upwardly from the base and a flat horizontally disposed cover fixed to and extending between the upper edges of the side walls, the cover having end portions overhanging the end walls and establishing downwardly facing stop shoulders, a substantially flat, rectangular arm rest related to each arm rest support to extend transverse of the frame, each arm rest having an upper portion normally projecting upwardly from the arm support to occur adjacent one end of the central seat portion and the back rest, and a lower portion depending between the arm rest support and the central seat portion, hinge means pivotally securing the upper portions of the arm rests to the tops of the arm rest supports, and actuating means carried by the frame and connected with the arm rests and operable to pivot the arm rests to a position where their upper portions project longitudinally outward from the tops of the supports and their lower portions are brought into cooperative engagement with a central seat portion to establish a couch, each arm

rest having a frame with a stop at the lower portion thereof and adapted to engage the stop on the central seat portion when the arm rest is actuated, the actuating means including, a reversible electric motor carried by the frame, a reduction gear with a drive pulley carried by the frame and connected with the motor, a driven pulley wheel carried by the frame, a pulley belt between the drive pulley and the driven pulley wheel, and a link extending between and pivotally connected with the lower end portion of each arm rest and the pulley wheel.

7. A convertible chair and couch of the character referred to including, an elongate frame having a flat horizontally disposed base with parallel front and rear sides and parallel ends, flat vertically disposed rectangular arm rest supports projecting upwardly from the ends of the base and extending transverse the base, a box-like central seat portion projecting up from the center of the base and extending transverse the base, and a flat substantially vertically disposed back rest projecting upwardly from the back side of the central seat portion, the central seat portion having longitudinally spaced vertical side walls projecting upwardly from the base and a flat horizontally disposed cover fixed to and extending between the upper edges of the side walls, the cover having end portions overhanging the end walls and establishing downwardly facing stop shoulders, a substantially flat, rectangular arm rest related to each arm rest support to extend transverse of the frame, each arm rest having an upper portion normally projecting upwardly from the arm support occur adjacent one end of the central seat portion and the back rest, and a lower portion depending between the arm rest support and the central seat portion, hinge means pivotally securing the upper portions of the arm rests to the tops of the arm rest supports, and actuating means carried by the frame and connected with the arm rests and operable to pivot the arm rests to a position where their upper portions project longitudinally outward from the tops of the supports and their lower portions are brought into cooperative engagement with the central seat portion to establish a couch, each arm rest having a frame with a stop at the lower portion thereof and adapted to engage the stop on the central seat portion when the arm rest is actuated, the actuating means including, a reversible electric motor carried by the frame, a reduction gear with a drive pulley carried by the frame and connected with the motor, a driven pulley wheel carried by the frame, a pulley belt between the drive pulley and the driven pulley wheel, and a link extending between and pivotally connected with the lower end portion of each arm rest and the pulley wheel, one arm rest support being of sufficient vertical extent so that the arm rest pivoted thereto is in a horizontal plane when fully actuated and stopped, the other support being of greater vertical extent so that the arm rest pivoted thereto is in an inclined position when fully actuated and stopped.

8. A convertible chair and couch of the character referred to including, an elongate frame having a flat horizontally disposed base with front and rear sides and parallel ends, flat vertically disposed rectangular arm rest supports projecting upwardly from the ends of the base, a box-like central seat portion projecting up from the base and spaced from the arm rest supports, and a flat substantially vertically disposed back rest projecting upwardly from the back side of the central seat portion, a substantially flat, rectangular arm rest related to each arm rest support to extend transverse of the frame, each arm rest having an upper portion normally projecting upwardly from the arm support to occur adjacent the central seat portion and the back rest, and a lower portion depending between the arm rest support and the central seat portion, hinge means securing the upper portions of the arm rests to the tops of the arm rest supports, and actuating means carried by the frame and connected with the arm rests and operable to pivot the arm

arm rests to a position where their upper portions project longitudinally outward from the tops of the supports and their lower portions are brought into cooperative engagement with the central seat portion to establish a couch, the actuating means including, a reversible prime mover carried by the frame, a pulley wheel carried by the frame and driven by the prime mover, speed reducing means between the prime mover and the pulley wheel, and a link extending between and pivotally connected with the lower end portion of each arm rest and the pulley wheel, the links being fixed to the pulley wheel so that the arm rests are shifted from one position to the other upon rotating of the pulley wheel in excess of 180° in one direction or the other and so that the links cross the central axis of the pulley wheel, and stop means limiting rotation of the pulley wheel including, a stop mem-

ber projecting from the pulley wheel and a pair of stops carried by the frame and spaced circumferentially about the pulley wheel, the prime mover and the speed reducing means being positioned on the base within the box-like seat portion of the frame and the pulley wheel being rotatably secured to the back side of the back rest of the frame.
